US0D1067541S

(12) **United States Design Patent** (10) **Patent No.:** **US D1,067,541 S**
(45) **Date of Patent:** **** Mar. 18, 2025**

(54) **PET WATER DISPENSER**

(71) Applicant: **Chenyu Zhang**, Wenzhou (CN)

(72) Inventor: **Chenyu Zhang**, Wenzhou (CN)

(**) Term: **15 Years**

(21) Appl. No.: **29/977,143**

(22) Filed: **Dec. 5, 2024**

(30) **Foreign Application Priority Data**

Sep. 30, 2024 (CN) 202430627102.0

(51) **LOC (15) Cl.** **30-07**

Primary Examiner — Susan Moon Lee

(57) **CLAIM**

The ornamental design for a pet water dispenser as shown and described.

DESCRIPTION

FIG. 1 is a front, left, and top perspective view of a pet water dispenser, showing my design;
FIG. 2 is a rear, right, and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines depict portions of the pet water dispenser that form no part of the claimed design.
